UNITED STATES PATENT OFFICE.

GEORGE E. FRISZ AND JAMES D. WILTSHERE, OF INDIANAPOLIS, INDIANA; SAID WILTSHERE ASSIGNOR TO SAID FRISZ.

PULLING IMPLEMENT.

1,347,809.

Specification of Letters Patent. Patented July 27, 1920.

Application filed July 3, 1919. Serial No. 308,381.

To all whom it may concern:

Be it known that we, GEORGE E. FRISZ and JAMES D. WILTSHERE, citizens of the United States, residing at Indianapolis, in the county of Marion and State of Indiana, have invented certain new and useful Improvements in Pulling Implements, of which the following is a specification.

The present invention relates to wheel pulling implements of that type comprehended by our previous application, Serial Number 242,799, filed July 1, 1918, these improvements representing certain modifications and refinements in the structure looking toward a greater facility of operation and an increase in the general adaptation of the device for doing work along the line of removing or displacing of parts more or less difficult of accomplishment under ordinary conditions.

More specifically, this invention provides for greater ease in the application or removal of the object engaging members or arms such that the operations aforesaid may be accomplished without the complete disengagement of the means for holding them in proper position upon the body part of the puller; for the formation of the object engaging parts in such manner that turning or twisting thereof when stress is placed upon them in use will be precluded; and for other structural improvements giving greater range of application, as above premised.

This invention further comprehends a different type of clamping or gripping means from that used in the device of the previous application, the said means being so constructed that when the pulling implement is operated and engaged with it the gripping action increases as the stress or pressure is increased, thereby providing for positive engagement with the part being removed.

These and such other objects as may hereinafter appear are attained by the novel construction, combination and arrangement of parts to be hereinafter specifically described and claimed. Reference will now be had to the accompanying drawings forming a part of this specification, wherein:

Figure 1 is a side elevation of the device showing its application for the removal of a vehicle wheel by engagement with the threaded hub;

Fig. 2 is a sectional view showing more clearly the construction of the body of the

puller, especially with reference to the slot formation;

Fig. 3 is a perspective view of one of the puller arms;

Fig. 4 is a view showing the use of the device as a portable press, including a press plate or base;

Fig. 5 is a plan view of said press plate;

Fig. 6 is a fragmentary view showing the application of the puller arm to a wheel stud as when removing a wheel from a full floating axle; and

Figs. 7 and 8 are detail views of the thread engaging clamping rings, shown also in Fig. 1;

Fig. 9 is a sectional view of one of the puller arms.

Throughout the following detail description and on the several figures of the drawings, similar parts are referred to by like reference characters.

Taking up in detail the specific description of our present invention, 1 denotes the body portion of the device which consists of a heavy metallic disk having a central threaded hub 2 in which is received the pressing member or screw 3. The screw terminates in a pointed extremity 4 and being of special tool steel this point will withstand great pressures without mutilation, 80 said screw being operable by means of a wrench engageable with the head. It will be noted that the body 1 is formed with a series of slots of peculiar form, radial at 5 and enlarged laterally at 6 for the special purpose to be hereinafter set forth. As in our previous invention we use with this body a plurality of pulling arms 7, each of which in the present instance is threaded the greater portion of its length to receive 85 two or more nuts 8 for clamping the arms to the body. These arms are flattened at opposite sides so that when they are inserted in the slots 5 which conform in width to the thickness of the arms, turning or twisting 90 or said arms will be impossible. Furthermore, the ends of each arm are bent as indicated at 9 and 10, respectively, to provide hooks for engaging the parts to be removed.

One of these bent ends, as more clearly 105 shown in Fig. 3, is apertured at 11 to receive cap-screws or studs of a wheel in gear or wheel removing, as depicted in Fig. 6. It should be noted, furthermore, that the hooked ends are bent in different directions 110

- which arrangement is extremely useful because said arms may be turned in different directions as found desirable for convenience in attachment without in any way impairing their pulling powers. Before leaving this phase of the construction it will be explained that the arms are adjustable in the slots 5 radially, or outwardly and inwardly, to accord with the dimension of 5 the part or parts with which the arms are to be engaged and where necessary, or when there is any likelihood that the arms will shift or spread outwardly upon application of pressure, such tendency may be overcome 10 by the use of set screws introduced into the peripheral threaded openings 12, as fully described and shown in our previous application. These screws are not here shown because their use is entirely apparent. 15
- 20 An important feature of the construction of the body 1 is the provision of the laterally enlarged portion of the slots designated 6, for whenever it is desired to shift these arms 7 from one slot to another or to remove 25 them from the device, it is only necessary to release the nuts 8 if they are in clamping position and run the arms outwardly to said enlarged portion which is of sufficient size to permit the nuts to pass through. In 30 our previous device, one of the nuts had to be removed, but this is now not necessary, resulting in the saving of much time.
- The puller device as described above, when used in conjunction with a base or 35 press plate, becomes a portable press of great power, the operation of which is simply a carrying out of the functions of the apparatus differing but slightly from the pulling operations. The press plate is shown 40 in Fig. 5, denoted 13, having slots 14 at its sides and the intermediate cut-out portion 15. The arms 7 are engaged in the slots 14 in the manner shown in Fig. 4, and with this arrangement, for example, it is a simple 45 matter to push out the piston pin of a piston by placing the piston on the base and exerting pressure against the pin with the pressure screw 3. Many other simple operations can be carried out by this arrangement. 50
- Passing now to another important feature of our present device and referring again to Fig. 1 of the drawings, in removing a wheel by engagement with the threaded hub thereof, we employ a special clamp 55 consisting of the inner, internally threaded open ring 16 of Fig. 7, the outer peripheral surface of which is beveled as indicated at 17, and the outer clamping or closed ring 18 60 of Fig. 8, the inner periphery of which is correspondingly beveled so as to ride upon the beveled surface 17. Thus when removing a vehicle wheel, the outer ring 18 is first slipped over the threaded hub 65 19, then the inner ring is screwed on to the hub a suitable distance and the outer ring engaged therewith. The puller device hereinbefore described is now applied by engaging the hooked ends of the arms 7, any suitable number of which may 70 be used, over the outer ring 18 and the pressure screw 3 against the axle or shaft of the wheel. By producing pressure with said screw, the wheel is readily removed, the greater the pressure used, the greater 75 the clamping action of the rings upon the hub, eliminating the chance of stripping the threads or injuring the wheel hub. It should be understood that a ring 16 of the proper thread must be utilized to take the 80 particular hub threads, but these are more or less standard at the present time for numerous types of cars.
- Where it is desired to distribute the stress applied in the pulling of wheels, other arms 85 7 may be inserted in the vacant slots and engaged with other parts of the wheel than the threaded portion of the hub, such as with the spoke or with the stud, as shown in Fig. 6. 90
- Having thus described our invention, what we claim as new is:—
1. In an implement of the class described for removing wheels, pulleys, gears and the like from their shafts, the combination of 95 a body having slots extending radially and circumferentially therein, a pressure applying member carried by said body, and object engaging means adjustably mounted on said body in the slots and displaceable from said slots upon movement to the circumferentially extending portion thereof.
  2. In an implement of the class described for removing wheels, pulleys, gears and the like from their shafts, the combination of a 100 body having slots therein, a pressure applying member carried by said body, object engaging means adjustably mounted in the slots, and clamping means coöperating with the engaging means aforesaid and the body 105 for holding the engaging means in adjusted position against movement toward or from the pressure applying member, said engaging and clamping means being applicable and removable through the slots of the body. 110
  3. In an implement of the class described for removing wheels, pulleys, gears and the like from their shafts, the combination of a body, a pressure member mounted therein, and pulling arms adjustably mounted on 115 said body, the latter having slots therethrough, said slots being relatively narrow at one end to engage and positively hold the arms against rotative movement.
  4. In an implement of the class described 120 for removing wheels, pulleys, gears and the like from their shafts, the combination of a body, a pressure member mounted therein, and pulling arms adjustably mounted on said body and flattened at the sides thereof, 125

the body having slots therethrough, said slots being relatively narrow at one end to engage and positively hold the arms against rotative movement and relatively larger at 5 their other ends to permit free movement of the arms on or removal from the body.

5. A wheel puller of the class described comprising clamping means adapted for engagement with the wheel, said means consisting of a contractible member and a co-operating non-contractible member, the former having its inner peripheral surface formed with gripping means, and pressure producing means engageable with the latter 10 member and operable to effect contraction of the former whereby to clamp the part to be removed.

6. A wheel puller of the class described comprising clamping means adapted for engagement with the threaded portion of the hub of the wheel, said means consisting of a contractible ring internally threaded to correspond with the hub thread and means for engaging the peripheral portion of said 25 ring to produce contraction, and pressure producing means engageable with the last mentioned engaging means to effect contraction of said ring as aforesaid.

7. A wheel puller of the class described comprising clamping means adapted for engagement with the wheel, said means consisting of an inner open ring capable of being contracted and adapted for engagement with the part to be removed and an outer annulus adapted to slide upon said ring, and 35 means for exerting pressure upon the annu-

lus to cause the latter to slide upon the ring and thereby produce contraction for gripping the object.

8. A wheel puller of the class described 40 comprising clamping means consisting of a continuous inner ring split at one point and of yieldable material and having its outer peripheral surface beveled and a closed outer ring having its inner periphery correspondingly beveled to permit it to ride upon the inner ring, and pressure producing means for causing the outer ring to slide upon the inner ring to thereby produce clamping action.

9. An implement of the class described 45 comprising a body portion, a pressure producing member carried thereby, gripping arms mounted in said body portion, and a base or press plate with which the arms are adapted for movable engagement, to provide for adjustment of the pressure producing member with respect to an object arranged on the base with which said member is engageable substantially as described.

10. An implement of the class described 50 comprising a body portion having slots therethrough, a pressure producing member carried thereby, gripping arms mounted in said body portion and movable in the slots 55 for adjustment purposes, and a base or press plate also having slots in which the arms are insertible and adjustable horizontally.

In testimony whereof we affix our signatures.

GEORGE E. FRISZ.
JAMES D. WILTSHERE.
